CLAIM

The ornamental design for a water scooter, as shown and described.

DESCRIPTION

FIG. 1 is a left, front perspective view of a water scooter;

FIG. 2 is a right, front perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The portion of the article shown in broken lines is for illustrative purpose only and forms no part of the claimed design.
